UNITED STATES PATENT OFFICE

JOSEPH A. KUENZ, OF TOLEDO, OHIO.

DESIGN FOR AN AUTOMOBILE-RADIATOR.

47,775.

Specification for Design. Patented Aug. 31, 1915.

Application filed March 29, 1915. Serial No. 17,936. Term of patent 7 years.

To all whom it may concern:

Be it known that I, JOSEPH A. KUENZ, a citizen of the United States, residing at Toledo, in the county of Lucas and State of Ohio, have invented a new, original, and ornamental Design for Automobile-Radiators, of which the following is a specification, reference being had to the accompanying drawing, forming part thereof.

The figure is a front view of an automobile radiator, showing my design.

I claim:

The ornamental design for an automobile radiator as shown.

JOSEPH A. KUENZ.

Witnesses:

F. E. AUL,
M. H. MAYERS.
